COTTON GIN EMBODYING IMPROVED PNEUMATIC DOFFING MECHANISM

Arvel L. Vandergriff, Columbus, Ga., assignor to Lummus Cotton Gin Company, a corporation of Georgia

Application June 9, 1950, Serial No. 167,209

3 Claims. (Cl. 19—59)

My present invention relates to cotton gins and relates more particularly to cotton gins embodying some of the features of the improved doffing mechanism shown, described and claimed in my co-pending application, Serial No. 36,935, filed July 3, 1948, now Patent Number 2,588,593 entitled "Pneumatic Doffing Mechanism for Cotton Gins and the Like."

My present invention has for an object the provision of doffing mechanism for association with a cotton gin of the saw type embodying a lint duct open at its upper end, a separate air nozzle for each saw, and means positioning the upper edge of the forward wall of the lint duct, called the mote board lip, at a point substantially outwardly of the line of tangency along which lint and trash leave the saw cylinder, whereby the trash continues over the top of the mote board lip and the lint enters the lint duct, such apparatus being more effective in removing trash from the lint than prior doffing means.

Another object is to reduce the pressure of the streams of doffing air, thereby reducing the power required to operate the system and permitting the mouth of the lint duct to be narrowed without loss of lint, consequently decreasing the amount of trash drawn into the lint duct.

A more specific object is to provide pneumatic doffing mechanism for the saw cylinder of a gin embodying the combination of means for reducing the cross sectional area of the doffing nozzle embodying spacers disposed between the saws and means to maintain the lint duct under vacuum, whereby the velocity of the air induced into the open upper end of the lint duct is increased, permitting the forward wall or mote board lip of the lint duct to be moved further outwardly of the line of tangency along which the lint and trash leave the saw cylinder, further increasing the cleaning action of the apparatus.

A further object is to provide improved spacers for dividing the continuously extending doffing nozzle into a plurality of individual nozzles, one for each saw, which spacers shall be formed integrally in groups, thus facilitating the installation of the same within the gin and simplifying the manufacture thereof.

Briefly, I have discovered that the lint cleaning efficiency of a gin embodying generally the features of the above identified application can be greatly improved. With an 80 saw gin of the type disclosed in said application delivering air and lint to a standard lint flue and condenser of ordinary type, there exists in the gin lint duct a pressure of approximately $\frac{1}{10}$ inch, water gauge. This varies slightly with the size and length of the lint flue, namely the conduit leading from the gin lint duct to the condenser, the size of the condenser, and more especially with the thickness of the bat on the condenser screen drum. I have found that if the pressure in the gin lint duct exceeds about $\frac{1}{10}$ inch water gauge the velocity and volume of the air induced into the open ended gin lint duct is reduced enough to cause some lint not to enter the lint duct, wasting lint by discharging the same with the trash. Under $\frac{1}{10}$ inch water gauge pressure in the

5 gin lint duct, the pressure of the doffing air must be about 15 inches water gauge when the mouth of the line duct is approximately $1\frac{1}{4}$ inches wide. Doffing air under approximately this pressure is required to induce sufficient air at the correct velocity to turn all of the good lint into the gin lint duct. I have found that as the static pressure in the gin lint duct is reduced, the mouth of the lint duct can be narrowed since the lower the pressure in the lint duct the higher the velocity of the air induced thereinto.

10 In order to operate with the mote board lip at the optimum outward position relative to the line of tangency of the lint and trash leaving the saw cylinder, I provide means for maintaining the gin lint duct under vacuum on the order of $\frac{1}{10}$ inch water gauge. Such means preferably, though not necessarily, is in the form of a suction fan connected to exert suction on the condenser screen. Under these conditions I am able to reduce the doffing air pressure to approximately 6 inches water gauge. I thus effect a substantial saving in power required for moving air in the system since the suction fan operates against only one and one-half inches water gauge pressure to maintain the gin lint duct under $\frac{1}{10}$ inch water gauge vacuum. Supplying the induced air by maintaining the gin lint duct under vacuum has another important advantage. If the induced air is supplied by vacuum instead of by high velocity, high volume doffing air the induced air enters the mouth of the lint duct more evenly, making it more effective in turning the lint into the lint duct. Such even flow of air gives good lint-trash separation with about the same volume of induced air as when the apparatus is operated under 15 inches water gauge doffing air at $\frac{1}{10}$ inch lint duct pressure. Further, in an over moting gin, by decreasing the velocity of the jets of doffing air I materially reduce air currents which interfere with overhead moting and which tend to pull light trash from the edge of the mote belt into the gin lint duct.

15 In view of the foregoing it will be understood that the general object of my invention is to provide a gin in which there is a greatly improved separation of trash from the lint immediately adjacent the saw cylinder, and which prevents trash from being drawn into the lint duct, such general functional improvement being attended by the incidental improvements hereinafter appearing.

20 Apparatus illustrating the features of my invention is shown in the accompanying drawing forming a part of this application in which:

25 Fig. 1 is a detail transverse sectional view through a cotton gin having my improved doffing mechanism associated therewith;

30 Fig. 2 is a detail fragmentary view of the spacers associated with the saw cylinder and air doffing nozzle;

35 Fig. 3 is a detail sectional view taken generally along line III—III of Fig. 2;

40 Fig. 4 is a detail sectional view taken generally along line IV—IV of Fig. 2;

45 Fig. 5 is an enlarged diagrammatic view of the improved doffing mechanism, the view being essentially an enlarged cross-sectional view and showing a portion of the saw cylinder; and,

50 Fig. 6 is a detail sectional view taken generally along line VI—VI of Fig. 5.

55 Referring now to the drawing for a better understanding of my invention I show my improved doffing mechanism associated with a gin embodying the usual rotating saw cylinder 10 comprising individual, axially spaced saws 11. The saws are held in spaced apart relation on a shaft 12 by means of the usual spacers 13. The saws operate between huller ribs 14 and ginning ribs 16. Seed cotton to be ginned is fed into the breast 17 of the gin from a slide 18, and falls downwardly to be acted upon by the picker rolls 19 and 21 which present the cotton to the saw cylinder 10. In the manner understood, the

3
saws of the saw cylinder engage the seed cotton and pull the same through the huller ribs 14 into the roll box 20. Hulls removed from the cotton fall downwardly through a perforated plate 22 and are discharged by means of a conveyor 23 which may be located below the floor 24 of the gin house. Seed from which the lint has been removed fall downwardly between the ribs of the gin and are discharged through a seed conveyor 26. The gin may be provided with an overhead mote conveyor in the form of a flat belt 27 on which motes and trash thrown from the top of the saw cylinder are removed. The gin may also be provided with the usual mote board 28 onto which falls motes and trash thrown off by centrifugal force from the lower surface of the saws, such trash and motes sliding down the board 28 and being discharged along with the hulls by the conveyor 23.

On the rear side of the gin is an air chamber 29 extending substantially the length of the saw cylinder. The chamber 29 is supplied with air under pressure, as from a conduit 31.

The chamber 29 is defined by an upper wall 32 and a rear wall 33 forming one wall of a lint duct 34, together with a side wall 36. As best shown in Fig. 5, the inner edge of the upper wall 32 is turned downwardly as at 37. The rear wall 33 of the lint duct 34 is provided with an upwardly extending portion 38 terminating at 39 to the rear of and slightly above the portion 37 of wall 32. The two edges 37 and 39 cooperate to define between them an air nozzle 41 extending the length of the saw cylinder 10. The air nozzle is disposed to direct air in the chamber 29 downwardly and substantially tangentially of the saws to remove lint therefrom in the manner to be explained.

The lint duct 34 is defined between the walls 33 and a front wall 42. On the upper end of the front wall 42 is a slidable section 43 having its uppermost edge terminating as at 44 beneath the saw cylinder 10. The upper portion 38 of the wall 33 and the upper portion 43 of wall 42 thus define between them an open ended lint duct which is adapted to receive lint discharged from the saw cylinder. Lint is delivered through a flue 45 to a condenser 45a to which is connected a suction fan 45b.

Commencing at point 39 the portion 38 of the rear wall slopes first toward the saw cylinder 11 to a point 46, thence outwardly and downwardly to a point 47, 45 thence again inwardly and downwardly to a point 48. Just below the point 48 the upper section 38 of the wall joins with the upper edge of wall 33 through an airtight slip joint 50. The upper section 43 of wall 42 is provided at each end with a bracket 49 having therein a slot 51. The heads 52 of the gin are provided with substantially vertically disposed slots 53. The wall section 43 is adjustably secured by bolts 54 passing through the slots 51 and 53. Through the provision of a slip joint 56 the upper wall section 43 thus is adjustable toward and from the saws in a lateral direction as well as upwardly and downwardly relative thereto.

My improved form of spacers for dividing the nozzle 41 into a plurality of nozzles, and to provide spaces for receiving each of the saws 11 will now be described. As shown in Figs. 2 and 3 the spacers may be made in groups or units A and B. The section A may be the section of the spacers which fit adjacent the heads of the gin whereas, the sections B are the intermediate sections. The sections A and B comprise a body or base portion 57 having a shape to fit against the upper portion 38 of the wall 33. Each individual spacer C may have a rounded upper end 58 adapted to fit into the nozzle 41. The outer surface of each spacer C follows in general the cross sectional configuration of the wall section 38 with the exception that there is provided a flat section 59 on each spacer which overlies the point of bend 46 of the wall 38. As illustrated more particularly in Fig. 2 the upper ends 58 of the spacers, and the lower ends 60 thereof converge as viewed in plan thus to define an

5
opening between adjacent spacers which is flared at its inlet and discharge ends. The spacers are readily secured to the wall section 38 by means of bolts 60a and nuts 61 therefor. The bolts preferably have countersunk heads which lie flush with the spacers themselves.

It will be noted that the saws 11 have only a very minor peripheral portion thereof engaged in the channel like openings 62 between the spacers. The saw cylinder is disposed with the periphery of each saw running closely adjacent the bottom of the channel shaped openings.

10
15
20
25
By reference more particularly to Fig. 5 of the drawing, line X represents the line of tangency along which lint and trash leave the saw cylinder 10. My invention permits the upper edge 44 of the wall section 43 to be positioned at all times outwardly of the line of tangency of the lint and trash, namely, so that the lint and trash leaving the saws tangentially are not directed into the open mouth of the lint duct. Accordingly, when the gin is operating either with the higher pressure in the air supply chamber 29 and pressure in the gin lint duct 34 or with the lower pressure in chamber 29 and vacuum in lint duct 34, the induced air drawn into the mouth of the lint duct is sufficient to turn the lint without turning thereinto the trash.

30
35
40
While the improved functioning of a gin equipped with my improved doffing mechanism is due to a number of constructional features herein shown and described, it appears that the shape of the spacers and their disposition relative to the point at which the cotton is doffed from the saws is quite important. It will be noted that the spacers themselves and the plate or base portion A upon which they are cast turn abruptly away from the saws at the point P where lint and trash leave the saw cylinder. Due to this construction air induced into the lint duct commences immediately to act on the lint as soon as it leaves the saw cylinder, thereby to turn it into the mouth of the lint duct. Since the mote board lip 44 is vertically and horizontally adjustable I am enabled to set the same for optimum cleaning of cotton containing various types of trash and with cotton containing more or less moisture.

45
50
55
By way of example and not by way of limitation the following specific example is cited in order that the operation of the apparatus may be more clear:

55
60
65
70
75
"Within an 80 saw gin having a doffing nozzle approximately 63½ inches long, the upper ends of the spacers C are made so that when installed the total cross sectional area of the nozzle 41 is approximately 6 square inches. This amounts to a reduction in cross sectional area of the nozzle of more than 50 per cent over standard practice. When operating the gin with this nozzle under approximately 15 inches water gauge pressure in chamber 29, the mote board lip 44 is set approximately 1¼ inches away from the inner edge of the wall section 38 as measured along the line indicated at F, Fig. 5. Also, the edge 44 is set approximately ⅛ inch from the saw cylinder as measured along the line indicated at G. Under these conditions the initial direction of the doffing air is still above the mote board lip 44 and enough air is induced into the lint duct to turn the lint without turning thereinto trash traveling with the lint stream. The above setting holds good for cotton containing the normal amount of moisture, namely, approximately 6 per cent. If the moisture is below normal the mouth of the lint duct can be narrowed to approximately 1½ inches, and for very dry cotton to approximately 1 inch. If I now reduce the pressure in the lint duct 34 by means of the suction fan to about ¼ inch vacuum, water gauge, I can reduce the doffing air pressure to approximately 6 inches water gauge. Further, I am enabled under these conditions to close the mouth of the lint duct to approximately ¾ inch and can move the mote board lip to approximately 1¼ inch from the closest point on the saw cylinder as measured along line G. I note a considerable improvement in cleaning under the latter conditions. Since horsepower expended in moving air varies by the

three halves of the pressure I effect a considerable saving in power by operating with the lint duct under vacuum."

It will also be noted that by casting the spacers C in integrally formed groups, I greatly simplify the manufacture and accurate machining thereof as well as the installation of the same in the gin. It will be understood that the sides of the saws run closely to the sides of the spacers in the channel shaped openings 62. Actually, I find that lint being carried around on the saw cylinder flares outwardly therefrom and strikes the edges of the spacers C as well as engaging against the bottom of the channel shaped openings 62. This has the beneficial effect of disengaging trash from the cotton while on the saw cylinder, facilitating its separation.

From the foregoing it will be apparent that I have devised an improved doffing mechanism for cotton gins. It will be understood that the principal feature of my invention resides in apparatus in which the mote board lip is disposed outwardly of the line of tangency at which the cotton and trash leave the saw cylinder, permitting the operation of the apparatus without excessive loss of lint. In actual practice I have found that my improved doffing mechanism is especially effective for its intended purpose in removing from lint cotton the green leaf of the cotton plant as well as leaves from wild plants which may be mixed with the cotton and which attach themselves to the saws. This functional advantage is particularly important at the present time due to the wide use of mechanical harvesters which gather not only the cotton but also much trash, leaves and the like. When employed with a cotton gin embodying the overhead moting belt I have found that I not only increase the effectiveness of moting at the point where my improved doffing mechanism is placed but also improve the over moting characteristics of the gin. As before stated, this is due to the fact that my improved doffing mechanism does not draw from the edge of the belt motes which have been deposited thereon.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a cotton gin embodying a saw cylinder comprising a plurality of axially spaced saws, an elongated air doffing nozzle for directing air under pressure downwardly and tangentially of the saw cylinder to doff lint cotton and trash therefrom and move them in a continuous substantially straight path away from the saws, a lint duct having an open upper end defined by a rear wall and a forward wall spaced from the rear wall, the upper edge of said forward wall terminating below the point where the lint and trash are removed from the saw cylinder and outwardly of the line tangent to the saw cylinder at said point whereby the doffed lint and trash are di-

rected initially over and away from the open end of the lint duct, means on the rear wall dividing the same into a plurality of channel-shaped openings in which a segment of the periphery of the individual saws operate, means dividing the air doffing nozzle into a plurality of channel-shaped openings communicating with the channel-shaped openings for dividing the doffing air stream into individual streams of air, and means exerting suction on the lint duct sufficient to induce a stream of air thereinto which moves transversely of the individual streams of lint and trash moving above the open upper end of the duct to divert the lint into the duct without materially changing the direction of movement of the trash moving over the open end of the lint duct.

15 2. In a cotton gin embodying a saw cylinder having a plurality of axially spaced rotating saws, air doffing means disposed closely adjacent a side of the saw cylinder to direct doffing air tangentially of the saws downwardly and in a substantially straight path toward the bottom of the saw cylinder, thereby to doff lint and trash from the saws, a lint duct having an open upper end located below the point where the lint and trash are doffed from the saws and entirely outwardly from the line of tangency to the saw cylinder at said point and means to induce 20 into the open end of the lint duct a stream of air moving transversely of the doffing stream and effective to draw into the duct substantially only the lint.

25 3. In a cotton gin embodying a saw cylinder having a plurality of axially spaced rotating saws, air doffing means disposed closely adjacent a side of the saws comprising an individual nozzle for each saw operable to direct individual streams of air tangentially of the saws in a downward direction and toward the bottom of the saw cylinder to doff lint and trash from the saws and 30 move them along substantially straight parallel paths, a lint duct with an open mouth disposed at said side of the saw cylinder below and outside the line of tangency to the saw cylinder at the point where the lint is doffed from the saws and over the open mouth of which the said 35 lint-trash streams are directed by centrifugal force from the saws, and means to induce into the open mouth of the lint duct a stream of air moving transversely of the said 40 lint-trash streams to pull substantially only the lint from said lint-trash streams into the duct.
